CLAIM

The ornamental design for a material hold-down for laser crafting apparatus, as shown and described.

DESCRIPTION

FIG. 1 is a front, right, bottom perspective view of the material hold-down for laser crafting apparatus;

FIG. 2 is a rear, left, top perspective view of the material hold-down for laser crafting apparatus;

FIG. 3 is a front elevation view of the material hold-down for laser crafting apparatus, the rear elevation view being a mirror image of the front elevation view;

FIG. 4 is a left side elevation view of the material hold-down for laser crafting apparatus;

FIG. 5 is a right side elevation view of the material hold-down for laser crafting apparatus;

FIG. 6 is a top plan view of the material hold-down for laser crafting apparatus; and,

FIG. 7 is a bottom plan view of the material hold-down for laser crafting apparatus.

The shade lines in the figures show contour and not surface ornamentation. The broken lines in the figures show portions of the material hold-down for laser crafting apparatus that form no part of the presently claimed design.

1 Claim, 5 Drawing Sheets
